UNITED STATES PATENT OFFICE.

JOHN ZELLWEGER, OF ST. LOUIS, MISSOURI.

ROASTING-KILN.

No. 878,704.

Specification of Letters Patent.

Patented Feb. 11, 1908.

Application filed April 22, 1907. Serial No. 369,630.

To all whom it may concern:

Be it known that I, JOHN ZELLWEGER, a citizen of the United States, residing at St. Louis, Missouri, have invented a certain 5 new and useful Improvement in Roasting-Kilns, of which the following is a full, clear, and exact description, such as will enable others skilled in the art to which it appertains to make and use the same, reference 10 being had to the accompanying drawings, forming part of this specification, in which—

Figure 1 is a cross sectional view of a kiln constructed in accordance with my invention, the left hand half of this figure being 15 taken on the section line 1—1 of Fig. 4 and the right hand half being taken on the section line 1^a—1^a of Fig. 4; Fig. 2 is a cross sectional view, the left hand half of which is taken on the section line 2—2 of Fig. 4 20 and the right hand half of which is taken on the section line 2^a—2^a of Fig. 5; Fig. 3 is a cross sectional view taken on the line 3—3 of Fig. 4; Fig. 4 is a vertical longitudinal sectional view taken through the center of the 25 kiln; Fig. 5 is a horizontal sectional view taken on approximately the line 5—5 of Fig. 4; and Fig. 6 is a detail view illustrating a portion of the stirrer.

This invention relates to roasting kilns of 30 that type in which the gases emanating from the ore do not mingle with the fire gases by which the ore is heated.

One object of my invention is to provide means for utilizing the maximum of the heat 35 in the fire gases.

Another object is to produce and maintain the required temperature along the entire length of the hearth of the kiln.

Another object is to provide free access of 40 air to the material which is being heated. And still another object of my invention is to provide means for cooling the stirring apparatus which is used for turning over the material which is being heated.

45 The roasting kilns are either open kilns, in which the gases emanating from the ore mingle with the fire gases, or they are closed kilns, known as muffle furnaces, in which those two kinds of gases do not mingle.

50 The following description has reference to kilns which are constructed to supply heat to the ore during its roasting process:

In the open kilns the ore is heated, either 55 from above by radiation of heat from a flame and from the roof of the kiln chamber, or it is heated from below by conduction of heat

through the hearth from fire gases in flues or chambers underneath the hearth, or it is heated in both ways. In the closed kilns the ore always receives heat from the outside by conduction through the chamber or muffle walls, preferably, through the hearth. The most economical heating of ores can be effected in closed kilns from below, because in this case the heat reaches the ore before it can escape through the kiln walls and because the quantity of air passing through the kiln chamber can be limited to the amount necessary for the roasting process and there is then no excess of air to carry away heat.

In the under fired closed kilns or muffle furnaces used heretofore, a considerable quantity of heat is lost downwardly into the ground and sidewise through the flue walls to the outside. For the purpose of preventing the loss of heat downwardly I isolate the fire flues from the ground by air spaces underneath them and by heating in these flues the air which is necessary for the combustion of the fuel used in heating the hearth. The loss of heat from the fire flues sidewise to the outside is prevented in a great measure by air spaces in the walls of the outside flues and also air spaces between said walls and the side walls of the kiln chamber.

In the muffle kilns with bottom heat, as used heretofore, the fire-places are located only at one end of the hearth, which causes the temperature of the hearth to be high near the fire-place and low at a distance from the fire-place and, as a consequence, prevents a high output. This defect I remedy by producing heat underneath the hearth at different places along its longitudinal extent, and thereby replacing the heat which has been given up by the fire gases to the hearth. In this way I keep the temperature of the hearth up to a high degree and increase the capacity of the kiln. The fuel for such intermediate under fire is preferably gas or oil.

100 In the muffle kilns used heretofore, the sulfurous gases, owing to their great specific gravity, float near the surface of the ore and thereby prevent free access of the air to the ore. This defect I remedy by blowing air across the hearth, thereby clearing away the heavy sulfur gases and bringing fresh air in contact with the ore.

105 Referring to the drawings which illustrate the preferred form of my invention, 1 designates the hearth on which the ore is placed, said hearth being supported by a plurality of

parallel walls 2 which extend longitudinally of the kiln. The spaces between these walls are divided by horizontally disposed partitions 3 so as to produce fire flues 4 located 5 directly beneath the hearth and air ducts or flues 5 located beneath the fire flues.

The fire flues extend throughout the entire length of the hearth, and at several points along the length of the hearth are cross flues 10 or conduits 6 located beneath the fire flues and communicating therewith by means of ports 7, as shown in Fig. 4, fuel being supplied to these cross flues by means of conduits 7^a leading from gas producers 8, as shown in 15 Figs. 2 and 5. At the feed end of the kiln is a cross flue 6^a that communicates with the fire flues and leads to a chimney 9. Adjacent these cross flues 6 and 6^a are open-ended cross tunnels 10 which communicate with the 20 air ducts or flues 5, the rear ends of said air flues communicating with the fire flues by means of ports 11 so as to supply said fire flues with the air that is required to produce combustion of the fuel, said air being heated 25 as it passes through said air ducts. The walls 2^a of the two outside flues are located some distance inwardly from the side walls 12 of the kiln so that air spaces are produced 30 on the sides of the outside fire flues, these spaces constituting the wheel pits hereinafter described. Preferably, the walls 2^a are provided with air flues 5^a that communicate with the cross tunnels 10, ports 30 leading laterally from said flues so as to introduce 35 air into the kiln chamber laterally above the ore on the hearth, said air becoming heated as it passes through said flues 5^a so that it is introduced above the ore in a heated condition. These flues 5^a not only serve as a 40 means for introducing heated air laterally above the ore on the hearth but they also serve to isolate the outside fire flues and thus prevent the heat from escaping laterally from said flues.

45 From the foregoing it will be seen that the loss of heat downwardly from the fire flues is prevented by the air ducts 5 which isolate the fire flues from the ground, the loss of heat from the fire flues sidewise to the outside being prevented in a great measure by the air spaces between the outside flues and the side walls of the kiln and the air flues in the walls of the outside fire flues.

In order that there may be a free access of air 55 to the ore on the hearth, I have provided means for introducing blasts of air through the side walls of the kiln across the hearth so as to clear away the heavy sulfur gases which collect over the ore, this being accomplished by 60 a plurality of nozzles 14 connecting with supply conduits 15 and projecting through the side walls of the kiln, as shown in Figs. 1 and 2, the roof 12^a of the kiln being provided with an opening 16 through which the sulfur 65 gases escape, as shown in Fig. 4. While it

is preferable to provide nozzles 14 or similar devices for introducing blasts of air across the hearth, it is not absolutely necessary to the successful operation of my kiln that such devices be used, for the air that is introduced laterally above the ore by the air flues 5^a also serves to drive off the heavy sulfur gases that collect over the ore. If desired, these flues can connect with a source of air under pressure so as to produce lateral blasts of air over the ore, instead of communicating with the open-ended cross tunnels 10, as herein shown.

The ore or material that is to be roasted is introduced into a hopper 17 at the feed end 80 of the kiln, as shown in Fig. 4, and said material is fed onto the hearth 1 and also turned over from time to time by means of a stirrer 18 provided with wheels 19 that travel on tracks 20 in the wheel pits, as shown in Figs. 85 1 and 2, said stirrer being of substantially the same construction as that shown in my prior patent No. 627,609, dated June 27, 1899, and comprising a rotatable member 90 provided with a plurality of blades.

In Figs. 1, 3 and 4 I have only shown the stirrer diagrammatically as Fig. 6 illustrates the particular construction of the stirrer. It is immaterial, however, so far as my present invention is concerned what kind of a 95 stirrer is used so long as it will operate to turn over the material on the hearth. In order that this stirrer may be cooled off after it has passed through the kiln I have provided cooling chambers 21 at each end of 100 the kiln chamber. These cooling chambers are preferably formed of metal and are substantially I shape in cross section, as shown in Fig. 3, said chambers being provided at their outer ends with doors 22 so that the 105 kiln chamber is closed at both ends. An air chamber 23 extends over each of the cooling chambers and connects with a chimney 24 that creates a draft and thus causes a current of cold air to pass continually 110 through the air chamber 23 to keep the cooling chamber 21 at a low temperature.

At the rear end of the kiln is a pit 25 into which the roasted ore is dumped and the bottom of said pit is preferably provided with 115 doors that may be opened to discharge the contents of the pit into cars or other suitable conveyances. A chute 26 leads from the floor of the cooling chamber at the feed end of the kiln, and at the lower end of said 120 chute is a trough 27, the ore that the stirrer carries into the cooling chamber dropping down into said trough and being thereafter conveyed by some suitable means back to the hopper.

Having thus described my invention, what I claim as new and desire to secure by Letters Patent is:

1. A roasting kiln provided with a hearth, a heating chamber located beneath said

- hearth, and means for returning the heat which escapes downwardly and laterally from said chamber back to the chamber; substantially as described.
- 5 2. A roasting kiln provided with a hearth, a heating chamber located directly beneath the hearth, and an air chamber covering the bottom of said heating chamber; substantially as described.
- 10 3. A roasting kiln provided with a hearth, fire flues located underneath said hearth, and air flues or ducts surrounding the bottom and sides of said fire flues; substantially as described.
- 15 4. A roasting kiln provided with a hearth, and means for creating heat at several points underneath the length of said hearth; substantially as described.
5. A roasting kiln comprising a hearth, 20 heat flues located underneath said hearth and extending longitudinally thereof, means for supplying said flues with heat, and air ducts surrounding said flues; substantially as described.
- 25 6. A roasting kiln comprising a hearth, heat flues located underneath said hearth and extending longitudinally thereof, a plurality of cross conduits provided with ports which establish communication with the heat 30 flues, means for supplying air to said heat flues to produce combustion of the fuel; substantially as described.
7. A roasting kiln comprising a hearth, heat flues located underneath said hearth and extending longitudinally thereof, means for supplying fuel to said heat flues, air ducts arranged beneath the heat flues and in communication with said flues to supply air thereto to produce combustion of the fuel, 35 and a chimney communicating with said heat flues; substantially as described.
- 40 8. A roasting kiln comprising a hearth, fire flues located beneath said hearth and extending longitudinally thereof, a plurality of cross flues or conduits having ducts which lead to said fire flues, means for conducting fuel to said cross flues, air ducts incasing the bottoms of said fire flues and communicating with the interior thereof at the points where 45 the heat is created, and a chimney with which all of said fire flues communicate; substantially as described.
- 50 9. A roasting kiln comprising a kiln chamber, a hearth located inside of said chamber and supported by a plurality of walls that extend longitudinally of the kiln, horizontally disposed partitions which divide the spaces between said walls into a series of heat flues located directly beneath the 55 hearth, and a series of air ducts located underneath the heat flues, the walls of the outermost heat flues being located some distance inwardly from the side walls of the kiln chamber so as to provide air spaces, 60 means for supplying fuel to said heat flues at several points throughout the length of the hearth, and means for establishing communication between the air ducts and the heat flues; substantially as described.
10. A roasting kiln comprising a kiln chamber, a hearth for supporting the ore to be heated, means for creating heat beneath said hearth, and means for introducing blasts of air into said kiln chamber to drive off the heavy sulfur gases which collect over the ore; 70 substantially as described.
11. A kiln for roasting ore, comprising a kiln chamber, a hearth located inside of said chamber, means for creating heat underneath said hearth, and means for introducing 75 blasts of air through the side walls of the kiln chamber to dispel the heavy sulfur gases which collect over the ore; substantially as described.
12. A kiln for roasting ore, comprising a kiln chamber, a hearth arranged inside of said chamber, heat flues located beneath said hearth, a plurality of devices projecting through the side walls of the kiln chamber for introducing blasts of air into the interior 80 thereof and over said hearth, and means for supplying air to said devices; substantially as described.
13. A roasting kiln provided with a hearth, cooling chambers at the opposite ends of said hearth, means for keeping said cooling chambers at a low temperature, and a stirrer adapted to travel over the hearth to turn and agitate the material thereon and thereafter come to rest in the cooling chamber to 85 enable it to cool off; substantially as described.
14. A roasting kiln comprising a kiln chamber, a hearth arranged inside of said chamber, a stirrer adapted to travel over said hearth to agitate and turn the material thereon, cooling chambers located at the opposite ends of said kiln chamber and having their walls constructed of metal, air chambers extending over said cooling chambers, and 90 means for creating a draft of air through said air chambers; substantially as described.
15. A roasting kiln comprising a kiln chamber, a hearth located inside of said chamber for supporting the material to be roasted, a stirrer adapted to travel over said hearth for turning and agitating the material thereon, metallic cooling chambers at the opposite ends of said kiln chamber to receive the stirrer, and means for creating a current of 95 air over said cooling chambers to keep them at low temperature; substantially as described.
16. A roasting kiln comprising a kiln chamber, a hearth located inside of said chamber for supporting the material to be roasted, a stirrer adapted to travel over said hearth for turning and agitating the material thereon, cooling chambers at the opposite ends of said kiln chamber to receive the stirrer, and 100
- 115
- 120
- 125
- 130

means located underneath the cooling chamber at the feed end of the kiln to receive the material that the stirrer carries into said chamber; substantially as described.

- 5 17. A roasting kiln provided with a hearth, a plurality of fire flues located underneath the hearth, air flues covering the lower sides of said fire flues, and air flues formed in the walls of the outside fire flues and having lateral ports which introduce air laterally above

the material on the hearth; substantially as described.

In testimony whereof I hereunto affix my signature in the presence of two witnesses, this twentieth day of April 1907.

JOHN ZELLWEGER.
